JOSEPH DAVIDSON, OF GREENVILLE, SOUTH CAROLINA, ASSIGNOR OF ONE-HALF TO
AMERICAN MACHINE & MANUFACTURING COMPANY, A CORPORATION OF NORTH
CAROLINA.

AUTOMATIC VALVE FOR HYDRAULIC MACHINERY.

1,300,703.

Specification of Letters Patent. Patented Apr. 15, 1919.

Application filed August 8, 1916. Serial No. 113,701.

To all whom it may concern:

Be it known that I, JOSEPH DAVIDSON, a citizen of the United States, and resident of Greenville, county of Greenville, and 5 State of South Carolina, have invented an Improvement in Automatic Valves for Hydraulic Machinery, of which the following is a specification.

The object of my invention is to provide 10 a simple and efficient valve device, more especially adapted to hydraulic accumulator systems for automatically by-passing the water pressure whenever the accumulator is fully charged and for closing the by-pass 15 and forcing the water to enter the accumulator when the latter has discharged its water and requires a new charge.

My object is also to provide in a valve of 20 the foregoing character in which the by-pass valve, when partially opened by the direct action of the accumulator, is further quickly opened to the maximum degree by a counter-weight, so that the valve device is sensitively responsive to provide instant 25 relief from pump pressure upon the accumulator; the said counter-weight co-operating with the water pressure upon the valve stem to effectively and rapidly provide a full opening into the by-pass.

With these and other objects in view, my 30 invention consists of certain features of construction and combinations of elements as more fully set out in the following specification and pointed out in the claim.

My invention will be better understood 35 by reference to the drawings in which:—Figure 1 is a side elevation of a hydraulic accumulator having my improved automatic valve applied thereto; Fig. 2 is a sectional 40 elevation of an automatic valve embodying my invention; and Fig. 3 is an end view of the same on a small scale.

2 is the accumulator proper and may be 45 made in any of the well known forms, such for example as a cylinder in which a plunger operates and supporting a weight box which may contain suitable weight, which with the proportion of the plunger area determines the pressure per square inch available. I 50 do not restrict myself in any manner to a particular construction of accumulator, except that it shall provide a reciprocating motion for an operative part to actuate my improved valve.

55 Water is supplied to the accumulator cyl-

inder by a pipe 3, receiving its supply from the pipe 4 through the automatic valve 5. The hydraulic pump (not shown) supplies water at any given pressure into the pipe 4, and this pressure is transmitted to the accumulator.

The valve device proper is more fully shown in Figs. 2 and 3 and will now be described. A solid block of steel forms the body 5, and has a number of holes bored 65 into it which intercommunicate to form the through passage 6 having an angular portion forming a check valve seat 7, and a by-pass outlet 9 by which the water may be by-passed back to the pump when the accumulator is fully charged. The pipe 3 from the accumulator 2 communicates with one outlet of the passage 6, and the pipe 4 from the pump communicates with the other outlet of the passage 6. 8 is a ball check valve 75 seating upon the seat 7, and is guided in a recess in the bottom of a plug 20 screwed into an opening 20^a above the check valve seat 7. A packing washer 20^b insures a water-tight joint. This check valve retains 80 the pressure of the accumulator when the by-pass valve 11 is open. The by-pass valve 11 seats upon a seat 9^a at the inner end of the by-pass outlet 9, and has a stem 10 of slightly smaller cross section, said stem ex- 85 tending up through a plug 13 which is screwed into the top of the body 5 in alignment with the valve seat 9^a. This plug clamps in position an annular leather packing 12 which surrounds the stem 10 and 90 forms a water-tight joint. The plug 13 being of considerable height, forms a good substantial guide for the stem 10 of the by-pass valve. At its top it is provided with a yoke 14 pivoted to a lever 15, and by which 95 it is reciprocated. This lever 15 is fulcrumed at 17 in a yoke 16 having a shank screwed into the body to one side of the by-pass valve. The lever 15 has a slotted opening 18 through which the pin 17 extends, so that the said lever may have longitudinal play when being rocked. The lever 15 is extended beyond the fulcrum pin 17 and provided with an adjustable counter-weight 19 having a clamping screw 19^a, 100 whereby any degree of counterweight required may be provided. The other end of the lever 15 is extended beyond the body 5. At this end of the body, I provide two upright angle irons 25 bolted to the body at 110

their lower ends, and at their upper ends connected by a transverse guide block 24. This guide block 24 is provided with a square hole in which is guided the lower end 5 portions 21 and 22 of the rod 23 which is reciprocated vertically by the accumulator. The rod 23 may be round and screwed into the top of the part 22 to which is riveted a U-shaped bar 21, thereby forming a vertical slot 21^a through which the lever 15 extends. When the rod 23 is lifted, the bottom of the slot 21^a strikes the lever 15 and lifts it to open the by-pass valve 11; and when the rod 10 is lowered the top of the slot 21^a (bottom of part 22) strikes the lever and depresses it to lower and close the by-pass valve 11. The closing is gradual and the pressure of the water acting upon the shouldered portion of the head positively holds the valve closed 15 thereafter until forcibly lifted. When the rod 23 is lifted, it will continue to rise until the bottom of the slot 21^a lifts the lever 15 just sufficiently to relieve the pressure which holds the by-pass valve closed, and then the 20 counterweight 19, assisted by the hydraulic pressure beneath the valve 11, quickly forces the lever 15 upward to fully open the by-pass, the movement of the lever end being permitted by the slot 21^a above it.

25 The rod 23 may be operated in any suitable manner, and a convenient construction for this purpose is shown. In this case, the rod extends through the bracket 26 and has a collar 27 secured to it below the bracket 30 and a second collar 28 at its upper end. A spring 29 fits loosely around the rod and rests upon the bracket 26. The bracket is secured to the movable weight box of the accumulator 2, and in rising and falling 35 operates upon the collars 27 and 28 alternately, the downward movement being positive and the upward movement being made through the spring 29. In this way, the closing of the by-pass valve is insured in a 40 slow or gradual manner, but the opening movement is done in a rapid manner by the combined operation of the counterweight 19 and the force of the water in passage 6 acting upon the valve 11 at the moment of lifting it. The spring 29, lifted by the bracket 45 26, presses upon the underside of the collar 28 and transmits the force acting to lift the rod 23 until it overcomes the resistance of the lever 15 and valve 11 to movement, after 50 which said lever is free to move in the slot 21^a and is oscillated rapidly by the counterweight 19 as above stated. By adjusting the counterweight 19 upon the lever 15, its effective power may be increased or decreased to compensate for any difference in 55 hydraulic pressure which may be employed in the passage 6, for it is manifest that, with a given difference in areas of the valve piece

11 and its stem 10, any difference in water pressure in the thoroughfare or passage 6 65 will require a difference in the effective power of the counterweight through adjustment of its leverage.

I have described my improved automatic pressure regulator valve as applied to the 70 control of accumulators, but I do not limit myself to such use as it may be employed in any other manner as for example in the direct control of hydraulic machinery to limit the maximum pressure to be applied 75 with a continuously operating pump; and while the valve is especially intended for hydraulic, the fluids to be controlled may be of other natures, such as oil.

I have described my invention in the form 80 which I have found to be suitable for commercial use, and while I prefer the details of construction as shown, I do not restrict myself thereto as they may be modified without departing from the spirit of the invention.

Having now described my invention, what I claim as new and desire to secure by Letters Patent, is:

A pressure regulator valve, comprising a 90 body having a thoroughfare provided with inlet and outlet ports, a check valve between them, a by-pass opening from the thoroughfare between the check valve and the inlet port, a by-pass valve controlling the by-pass opening having a stem extending to the outside of the body, operating means for the by-pass valve consisting of a counterweighted lever operatively connected with the stem of the by-pass valve and with the 100 body, and operating means for the lever permitting of free oscillation in a vertical direction under the action of the counterweight, said means characterized by having a vertically reciprocating rod provided with 105 a slotted lower portion through which the end of the lever extends and in which it has a large free play in a vertical direction and a guiding means on the body close to the reciprocating slotted portion of the vertical 110 reciprocating rod whereby the lever is guided in a vertical direction and held against lateral displacement, said guiding means also having at its upper part an overhanging guide through which the slotted lower portion of the reciprocating rod is guided to maintain its slotted opening in alignment with the guiding means and with the lever end.

In testimony of which invention, I here- 120 unto set my hand.

JOSEPH DAVIDSON.
